GUSTAV G. GOCKE, OF YORK, NEBRASKA.

RECOIL-REGISTER.

1,150,756.

Specification of Letters Patent. Patented Aug. 17, 1915.

Application filed June 26, 1915. Serial No. 36,481.

To all whom it may concern:

Be it known that I, GUSTAV G. GOCKE, a citizen of the United States, residing at York, in the county of York and State of Nebraska, have invented certain new and useful Improvements in Recoil-Registers; and I do hereby declare the following to be a full, clear, and exact description of the invention, such as will enable others skilled in the art to which it appertains to make and use the same.

This invention relates to registers, and more especially to the means for operating the same; and the object of the invention is to register the number of shots fired by a gun. This object is carried out by providing means for mechanically counting the recoils of the gun, by which latter term as used in this specification I desire to be understood as including not only the ordinary rifle and fowling-piece but machine guns and larger pieces of ordnance to which the invention may be readily adapted. Registers of this character have hitherto been attached to or inserted in the gun-stock and actuated by the trigger or by the recoil. In the former instance the devices are not accurate, because occasionally the trigger is moved without firing the gun and therefore there is no recoil. Those devices which actuate the counter by recoil have always, as far as I am aware, exposed the face of the counter through the side of the gun-stock. I consider this objectionable because the counter should be in the upper edge of the gun-stock where it is more readily exposed to view and less liable to accidents. I overcome this and other objections by constructing my invention in the manner hereinafter described and claimed and shown in the drawings wherein:—

Figure 1 is a plan view of the rear end of a gun-stock equipped with this recoil register. Fig. 2 is an enlarged central longitudinal section through the gun-stock and the casing of my invention, showing the parts in full lines in normal position and in dotted lines in the position that they assume at the moment of recoil. Fig. 3 is a rear elevation of a gun-stock equipped with my invention, the shoulder plate being turned aside. Fig. 4 is a perspective detail of the frame. Fig. 5 is a perspective detail of the rocking pin.

In the drawings the letter G designates a gun which might be a machine gun or a

larger piece of ordnance, although in the present instance I have shown only the rear end of the stock of an ordinary shot gun or the like, the same being generally made of wood and having a shoulder plate P secured to its rear end by screws S or otherwise. The letter C designates a registering mechanism, such for instance as the Veeder counter, to whose details of construction no claim is made; and it is quite obvious that any other suitable counter could be employed in its place.

Coming now to the details of the present invention, I provide the gun-stock with a chamber 1 opening out its rear end at 2 so that it may be covered by the plate P when the latter is fastened in proper position, and having an opening through the top or upper edge of the stock covered with glass 3 so that the counter C may be seen therethrough. As seen in Fig. 3 the upper portion of this chamber is made substantially tubular, and its rear end has a notch or recess 4 to receive the foot 5 of the frame 6, which foot may be held to the stock by screws 7. Said frame is preferably formed of a single piece of metal bent to the shape best seen in Fig. 4, its body being provided with slots 10 and 11 set oblique to its length and at an angle to each other, its front end 12 being upturned and pierced with an eye, and its rear end 13 being also upturned and provided with a socket, and carried down into said foot 5. Mounted in said socket 13 is the rear end of a rod 15 which passes completely through the counter C and extends through the eye in the upturned front end 12 of the frame, and this end of the rod has a long thread 16 cut thereon as seen in Fig. 2. On this thread run barrel nuts 16 and 17 resting against opposite sides of the front end 12 of the frame, whereby the rod is held removably and adjustably in place. This rod forms a guide for the longitudinal movement of the counter and the rocking pin described below.

Depending from the casing of the counter is a pin 21 movably engaging the rear slot 11, while a rocking pin 20 has its lower end movably engaging the forward slot 10 and its body connected with a tubular shaft 22 which surrounds the rod 15 and extends into and is connected with the mechanism for advancing the unit wheel of the counter step by step. I have not illustrated in detail how this connection is effected, first because

it forms no part of my invention, and second because the connection may have to be varied to adapt it to different types of counters. It is only necessary that an oscillation of the 5 tubular shaft with respect to the casing of the counter will actuate the latter. The upper end of said rocking pin is preferably split as at 23 and passed astride the tubular shaft, its arms being drawn together upon 10 said shaft by means of a screw 24. A long and extremely sensitive coiled spring 25 surrounds the rod between the rocking pin and a head 26 on the forward end of the rear barrel nut, and it is obvious that this nut 15 may be adjusted to increase the tension on the spring.

With this construction of parts, the mechanism may be inserted into the rear end of the chamber 1 when the plate P is turned 20 aside as seen in Fig. 3, and is held therein by the screws 7, and then the plate is replaced and held by its screws S. When now the gun is fired the explosion causes a slight but quick recoil of the stock which of course 25 carries with it the frame, while the counter on account of its inertia tends to remain stationary. The result is that the forward slot 10 moves over the lower end of the rocking pin 20 and swings it to one side, while 30 the rearward slot 11 moves over the pin 21 and swings the casing of the counter C in the opposite direction. The tubular shaft to which the rocking pin is attached is therefore oscillated with respect to the casing, 35 and the unit wheel of the counter is set forward one step as is common in devices of this character. The rearward movement of the upturned front end 12 of the frame also causes the compression of the spiral spring, 40 and as soon as the force of the recoil has spent itself this spring expands and restores the parts to their original position. Meanwhile the dial or face of the counter has moved slightly forward from the position 45 shown in Fig. 1 and out of registry with the hole, but immediately resumes its proper position thereunder, and the marksman or hunter can look through this hole at any time and observe how many shots have been 50 fired. This register is made, as above stated, by means of the recoil rather than by movements of the trigger, and is therefore quite reliable. It will be observed that should the butt of the stock be dropped on the ground, 55 the register will not be actuated; and it is hardly likely that the open end of the barrel will ever be rammed against anything with sufficient force to actuate the mechanism described. While I have shown the frame as 60 provided with two oppositely inclined slots (or they might be merged into a single slot made angular between its extremities) so that the counter turns in one direction and the pin in the other, it will hardly require 65 further illustration to make it clear that if

either the counter or pin were turned to a greater degree the other element need not turn at all. However, I prefer the construction shown for the reason that a single oblique slot would require the frame to be 70 somewhat wider, and a wider frame would necessitate a chamber of such size that it might weaken the gun stock.

What I claim is:

1. A recoil register for guns comprising a 75 frame adapted for attachment to the gun stock and having an oblique slot, a longitudinal guide carried by said frame, a counter including a tubular actuating shaft slidably mounted on said guide, yielding means 80 for holding the counter at the rear end of the frame, and a swinging pin having one end secured to said shaft and the other end mounted in said slot.

2. A recoil register comprising a frame 85 adapted for attachment to a gun stock and having an oblique slot, a longitudinal rod carried by said frame, a counter including a tubular actuating shaft slidably and rotatably mounted on said rod, a spring for 90 holding the counter at the rear end of the rod, and a swinging pin secured to said shaft and movably mounted in said slot.

3. A recoil register comprising a frame adapted for attachment to a gun stock and having upturned ends and an oblique slot in 95 its body between them, a longitudinal rod extending between the ends of the frame above said slot, a counter including a tubular actuating shaft slidably and rotatably mounted on said rod, a spring for holding the counter at the rear end of the rod, and a swinging pin secured to said shaft and having its lower end movably mounted in said slot. 100

4. A recoil register comprising a frame adapted for attachment to a gun stock and having upturned ends and an oblique slot in 105 its body between them, a longitudinal rod extending between the ends of the frame above said slot, a counter including a tubular actuating shaft slidably and rotatably mounted on said rod, a swinging pin having its upper end split and secured to said shaft and its lower end movably mounted in said slot, a spring coiled on the rod and normally holding the counter and pin at the rear end of the frame, and nuts for holding the rod in place in said upturned ends. 110

5. A recoil register comprising a frame 115 adapted for attachment to a gun and having an oblique slot and a longitudinal guide, a counter slidably mounted on said guide and having a projecting actuating shaft, a pin fixed to the shaft and movably mounted in 120 said slot, and a spring holding the pin normally at the rear end of the slot, for the purpose set forth.

6. A recoil register comprising a frame 125 adapted for attachment to a gun and having

- an oblique slot and a longitudinal guide, a counter slidably mounted on said guide and having a projecting actuating shaft, a pin fixed to the shaft and loosely engaging said slot, a spring holding the pin normally at the rear end of the slot but yielding to the inertia of the counter, said pin adapted to turn the shaft in one direction as the pin moves forward in the slot, and means for simultaneously turning the counter in the other direction.
7. A recoil register comprising a frame adapted for attachment to a gun, a longitudinal guide in said frame, a counter movably mounted on the guide and having a projecting actuating shaft, yielding means for holding the counter at the rear end of the frame, and means on the frame for turning the counter in one direction on the guide and its shaft in the other direction as the counter moves toward the front end of the frame.
8. A recoil register comprising a frame adapted for attachment to a gun, a longitudinal guide in said frame, a counter movably mounted on the guide and having a projecting actuating shaft, a spring for holding the counter at the rear end of the frame, pins projecting from the counter and its shaft, and means on the frame engaging said pins for turning the counter and its shaft in opposite directions as the counter moves forward in the frame.
9. A recoil register comprising a frame adapted for attachment to a gun, a longitudinal guide in said frame, a counter movably mounted on the guide and having a projecting actuating shaft, pins depending from the counter and its shaft, the frame having oppositely inclined slots with which said pins engage, and yielding means for holding both pins normally at the rear ends of their slots.
10. In a recoil register for guns, the combination with a frame having upturned ends and oppositely disposed oblique slots in its body between them, and a guide rod connecting said ends; of a counter including a tubular actuating shaft slidably and rotatably mounted on said rod, a pin on the counter standing within the rearmost slot, a swinging pin on the counter-shaft standing within the foremost slot, and a spring coiled on said rod between the last-named pin and the front end of the frame.

In testimony whereof I affix my signature.

GUSTAV G. GOCKE.
